UNITED STATES PATENT OFFICE.

PIERRIE ANTHONY FLORIMONT, OF NEWARK, NEW JERSEY.

ATTACHMENT FOR GAS-FIXTURE KEYS.

SPECIFICATION forming part of Letters Patent No. 644,854, dated March 6, 1900.

Application filed May 27, 1899. Serial No. 718,617. (No model.)

To all whom it may concern:

Be it known that I, PIERRIE ANTHONY FLORIMONT, a citizen of the United States, residing at Newark, in the county of Essex and State of New Jersey, have invented certain new and useful Improvements in Gas-Fixtures, of which the following is a full and complete specification, such as will enable those skilled in the art to which it appertains to make and use the same.

This invention relates to gas-fixtures, and has more particular reference to a device of this class provided with means for locking the valve thereof.

With gas-fixtures in general use the valve is in constant danger of negligent and unintentional operation, causing loss of gas and occasionally loss of life and property.

The object of the present invention is to provide the valve of a gas-fixture with a simple automatic locking device by which the valve may be locked in any desired position and allowing of any desired flow or no flow at all of gas through the fixture.

My invention is fully disclosed in the following specification, of which the accompanying drawings form a part, in which like reference characters denote like parts in the several views, and in which—

Figure 1 is a side elevation of a gas-fixture constructed according to my invention; Fig. 2, an end view thereof, and Fig. 3 a section on the line 3-3 of Fig. 1.

Referring more particularly to the drawings, I provide a gas-fixture of the usual type and which consists of a pipe member 5, designed for attachment to the ordinary wall-plug or other gas-supply connection and having at its outer end the burner 6. Transversely of and communicating with the pipe member 5 is the usual conical valve-casing 7, in which is seated the usual conical plug-valve 8, provided with a finger-piece or handle 9, and the valve 8 operates, in connection with the casing 7, to check, increase, and diminish the flow of gas through the pipe member 5 to the burner 6. The casing 7 is segmentally cut away at its lower perimeter, as at 10, forming longitudinal shoulders 11, and the valve 8 is provided with a stop-pin 12, which operates, in connection with the shoulders 11, to

limit the rotation of the valve 8 in the two closed positions thereof.

Thus far the described fixture is as ordinarily constructed.

In the practice of my invention I provide the valve 8 adjacent to the thumb-piece 9 with a pair of parallelly-projecting lugs 13, provided with a transverse pivot-pin 14, upon which is coiled a spring 15, one end of which 60 engages the adjacent valve-plug 8 and the other end of which engages the outer end portion of a catch 16, provided with side bearings 17, which are mounted upon the ends of the pin 14 exterior of the lugs 13, said catch 65 extending within the plane of the edge of said thumb-piece.

The valve-casing 7 is provided upon the cut-away edge portion 10 thereof with an annular flange 18, which, as shown in the drawings, is of less depth and thickness than the shoulders 11 and terminates at each end at a short distance from said shoulders.

The catch 16 is pivotally mounted in such position upon the valve-plug 8 that the inner 75 end thereof registers radially with the pin 12 and extends beyond the same, resting normally upon the flange 18, but preferably not extending entirely to the inner edge of said flange to allow longitudinal adjustment of 80 the plug-valve 8 by means of the conical nut 20 upon the end thereof.

The operation of my improved fixture will be evident from the foregoing description when taken in connection with the accompanying drawings and the following statement thereof. When the gas is turned on and passing through the pipe member 5 and burner 6, the inner end 19 of the catch 16 rests upon the flange 18, being held thereon by the spring 90 15, and the pin 12 is out of engagement with either of the shoulders 11. When the gas is turned off, however, the pin 12 comes into engagement with one of said shoulders, and the inner end 19 of the catch 16 falls over 95 said pin into the space between the adjacent shoulder 11 and the corresponding end of the flange 18 and locks the valve-plug 8 against rotation in any direction. It may be freed from this position, however, by simply operating the catch 16 against the spring 15 and raising the inner end 19 thereof onto the 100

flange 18 or above the same, and the valve may then be readily turned as desired.

It is evident that many changes may be made in the construction and arrangement of the details of construction of my improved gas-fixture without departing from the principle thereof.

The catch 16 may be caused to lock the valve 8 in any point of its rotation, and the spring 10 15 may be of any form, as well as the catch itself.

Having fully described my invention, I claim as new and desire to secure by Letters Patent—

15 In a gas-fixture, a valve-casing, a valve operatively mounted therein, and provided with a thumb-piece, a shoulder formed upon said casing and extending partially thereabout, a flange formed upon said casing between and

separated from the ends of said shoulder, a 20 pin fixed in said valve and operating in connection with the ends of said shoulder, and a spring - actuated catch mounted upon said valve adjacent and extending within the plane of the edge of said thumb-piece and operating in connection with said flange, the relative arrangement and construction of parts being such that said catch engages either end of said shoulders synchronously with said pin, substantially as shown and described. 25

In testimony that I claim the foregoing as my invention I have signed my name, in presence of the subscribing witnesses, this 13th day of May, 1899.

PIERRIE ANTHONY FLORIMONT.
